UNITED STATES PATENT OFFICE.

GEORGE W. KOHLMETZ, OF CLEVELAND, OHIO.

DESIGN FOR A STOVE.

SPECIFICATION forming part of Design No. 31,012, dated June 13, 1899.

Application filed April 18, 1899. Serial No. 713,515. Term of patent 7 years.

To all whom it may concern:

Be it known that I, GEORGE W. KOHLMETZ, a citizen of the United States, residing at Cleveland, in the county of Cuyahoga and State of Ohio, have invented and produced a new and original Design for a Cooking Stove or Range, of which the following is a specification, reference being had to the accompanying drawing, forming part thereof.

10 The drawing shows a perspective elevation of my new design in a cooking stove or range, and the leading feature of the design consists in the new and original ornamental border-work displayed on the several doors. This

15 border or decorative outline *a* is common to all the several doors A, B, C, D, E, and F and is the distinguishing feature of each, not in the fact of the border itself as such, because borders on stove-doors are not new, but on

20 account of the new and original style of border, the same having a depressed or cameo scroll or figured ornamentation *c* in its surface and the polished or otherwise highly-finished surface up to the edges of the scrolls or figures.

25 In other words, a smooth surfaced border having fanciful ornamentation wholly below the level of its surface, as shown, and displaying a dull or dead surface.

The second feature of the design relates to the name-plate *G*, which is of oval pattern 30 and has a finely-hatched center *g* for the name and a depressed figured border *g'* in the same plane with the said hatched surface *g* relatively to the surrounding and higher outside brightened or lustrous surface *g''* of the said 35 plate.

The third feature of the design relates to the stove-doors having their borders *a* ornamented in cameo or depressed figured work *c*, as above described, and their central panel *d* 40 finished with decorations *d'* in relief, so that said figured work stands out upon the otherwise plain surface of the panel.

The fourth feature of the design comprises the stove as a whole, embodying the several 45 distinctive and special features of design, as hereinbefore described.

What I claim is—

The design for a stove, substantially as herein shown and described. 50

Witness my hand to the foregoing specification this 17th day of April, 1899.

GEORGE W. KOHLMETZ.

Witnesses:

H. T. FISHER,
R. B. MOSER.
